PAGE 3

FIG.3

Des. 212,344

PAGE 4

FIG.4

FIG. 5

FIGURE 1 is a front, top and side perspective view of a photolithographic plate making machine or similar article, showing our new design;

FIGURE 2 is a top plan view;

FIGURE 3 is a side elevational view;

FIGURE 4 is a front elevational view; and

FIGURE 5 is an opposite side elevational view thereof.

We claim:

The ornamental design for a photolithographic plate making machine or similar article, as shown.
